UNITED STATES PATENT OFFICE.

HERMAN KRUECKE, OF MILWAUKEE, WISCONSIN.

CARBONATOR.

1,232,694.

Specification of Letters Patent. Patented July 10, 1917.

Application filed April 5, 1915. Serial No. 19,114.

To all whom it may concern:

Be it known that I, HERMAN KRUECKE, a citizen of the United States, and resident of Milwaukee, in the county of Milwaukee and State of Wisconsin, have invented new and useful Improvements in Carbonators, of which the following is a description, reference being had to the accompanying drawings, which are a part of this specification.

10 This invention relates to apparatus for carbonating liquids to be used as beverages, such as soda water and the like, and has for its object to provide for the automatic supply of liquid and carbonic acid gas to the 15 apparatus for replenishing the supply of carbonated liquid to a predetermined amount as the carbonated liquid is drawn off for use, the water or other liquid and the carbonic acid gas being admitted to the apparatus in such a manner as to insure the 20 water becoming thoroughly charged so as to be available for use at once.

Another object of the invention is to perfect details of construction in a carbonator 25 of this character, as will later more fully appear.

With the above and other objects in view the invention consists in the carbonator as herein claimed, and all equivalents.

30 Referring to the accompanying drawings in which like characters of reference indicate the same parts in the different views:

Figure 1 is a central sectional elevation of a carbonator constructed in accordance with 35 this invention, the water valve being open;

Fig. 2 is a sectional plan view thereof on the plane of line 2—2 of Fig. 1;

Fig. 3 is a detail sectional view of the 40 water valve in its open position; and,

Fig. 4 is a similar view of the water valve in its closed position.

In these drawings 10 indicates a disk-like base having a gasketed annular groove in which is fitted a cylindrical casing 11, there 45 being a top 12, similar in construction to the base 10, fitting on the upper end of the casing, the base and top being clamped against the ends of the casing by means of bolts 13. A water supply pipe 14 from the city water

50 mains or other supply under pressure, containing a suitable filter 15 and a pressure reducing valve 16 and a pressure gage 17 connects with the center of the base 10, and directly thereabove and communicating therewith is a valve casing 18 threaded into the top of the base and containing a re-

stricted passageway through which slidably fits a tubular valve rod 19 with a nozzle 20 on its upper end having a single small opening to allow the water to issue therefrom in a fine jet directed vertically. A float 21 is adjustably secured on the valve rod 19 near its upper end and serves to lift said valve rod when the liquid within the casing has reached a predetermined level. The lower end 22 of the valve rod is closed and is preferably pointed to avoid unnecessary resistance to the flow of water, and a short distance from the lower end the valve rod has a series of small openings 23 which in the lower position of the rod, as shown in Figs. 1 and 3, are exposed beneath the reduced portion of the passageway through the valve casing 18 to permit the flow of water therethrough into the interior of the valve 75 rod and then out through the nozzle 20. The upper end of the valve casing 18 is recessed to form a packing gland with a curved bottom, and a gasket 24 of leather or other suitable material is seated on this 80 curved bottom of the packing gland with a similarly curved metal washer 25 seated thereon and held pressed tightly thereagainst by means of a screw plug 26 which is threaded in the recess and has an internal 85 diameter sufficiently larger than the valve rod to form a surrounding chamber within which travels an annular flange 27 of the valve rod to limit the movements of the valve rod by engaging the washer 25 and the 90 inwardly extending flange 28 at the upper end of the screw plug 26, the latter position of the parts being shown in Fig. 4. As long as the openings 23 of the valve rod are beneath the restricted portion of the passageway through the valve casing water will 95 flow therethrough with force, but upon the lifting of the valve rod by the action of the float 21, so as to carry the openings 23 beyond the leather gasket 24, the supply of 100 water is shut off and will remain so until the water level within the casing 11 is reduced by drawing carbonated water therefrom through a supply pipe 29 which passes through the top plate 12 of the casing. 105

Carbonic acid gas under pressure from a storage tank or other source is admitted to the casing through a pipe 30 which is threaded in the base and communicates with a coupling 31 threaded into the top of the 110 base and provided with a pair of tubular arms 32 having parallel horizontal tubes 33

extending therefrom across the bottom of the casing and provided with numerous perforations 34 in the bottom thereof through which the gas may escape into the casing whenever the counter pressure within the casing is less than the pressure at which the gas is supplied. Thus, whenever carbonated water is drawn from the casing through the pipe 29 not only is the water level within the casing lowered so as to admit a corresponding amount of water from the water supply, but on account of a reduction in pressure within the casing a supply of carbonic acid gas will be admitted at the bottom of the casing and will rise in very small bubbles distributed throughout the body of water in the casing so as to thoroughly carbonate the water if it has not been fully carbonated on its admission to the casing. Above the level of the water the casing contains carbonic acid gas so that the fine jet of water issuing from the nozzle 20 and striking against a disk 35 which is supported near the top of the casing directly above the valve rod 19 is broken into a fine spray to facilitate the absorption of the gas by the water. To further assist in exposing the greatest possible area of water surface to the carbonic acid gas, a basket 36 is suspended by wires 37 from the disk 35, though not interfering with the jet of water from the nozzle 20 because of a central, tubular wall 38 through which the jet passes, and this basket is filled with broken glass 39, or other insoluble, granular or crushed material to receive the water as it drops from the spray, and as said basket is provided with a perforated bottom the water drops therefrom through the volume of gas above the liquid level. The extensive area of water surface in covering the particles of glass in the basket 39 and in dripping through the space beneath the basket assures an intimate exposure of all particles of the water to the gas to facilitate the gas absorption and effectively carbonate the water.

The tubular stem 40 of the disk 35, by means of which it is secured to the top plate 12, has openings 41 above the disk 35 through which gas may pass into a coupling 42 threaded into the top plate 12 and containing a pressure gage 43 and a safety valve 44. This allows of an escape of compressed

gas if the pressure within the casing, as shown by the gage 43, becomes excessive.

By means of this invention a quantity of carbonated water or other liquid predetermined by the adjustment of the float 21 and the valve rod 19 is maintained ready for use, and as soon as a demand is made thereon by drawing off the carbonated liquid through the pipe 29 the lowering of the float 21 admits a fresh supply of water equal to the amount drawn off, and at the same time the reduction in pressure within the casing permits of an inflow of carbonic acid gas through the body of water in the casing, this replenishing supply of water and gas continuing until normal conditions as to liquid level and pressure are restored, when the back pressure checks a further inflow of gas and the upward movement of the float lifts the valve rod 19 so as to carry the openings 23 above the gasket 24, thus shutting off the inflow of water. The water which has been admitted has been effectively carbonated by being sprayed through the carbonic acid gas in the upper part of the casing and by being sprayed over the surface of the broken glass in the basket 36 and by dripping therefrom, but if the water has not absorbed as much gas as it is capable of doing it will have a further opportunity to become fully charged by the passage of the numerous small bubbles of gas rising therethrough from the tubes 33 before it is finally drawn off from the bottom of the casing through the pipe 29.

What I claim as new and desire to secure by Letters Patent is:

In a device for commingling gas and liquid, a main casing, a liquid supply connection leading thereto, a valve casing communicating with the liquid supply connection and having a contracted passageway, a tubular valve rod slidably fitting within the contracted passageway, said rod being closed at its lower end and being provided near its said end with a plurality of inlet openings, a nozzle at the upper end of the valve rod, and a float carried by the rod.

In testimony whereof, I affix my signature, in presence of a witness.

HERMAN KRUECKE.

Witness:

KATHERINE HOLT.
